INVENTOR

WILLIAM A. FENN.
By Milton E. Robinson

ATTORNEY.

UNITED STATES PATENT OFFICE.

WILLIAM A. FENN, OF WEST WINFIELD, NEW YORK.

TYPE-HOLDER.

SPECIFICATION forming part of Letters Patent No. 630,873, dated August 15, 1899.

Application filed August 26, 1898. Serial No. 689,547. (No model.)

To all whom it may concern:

Be it known that I, WILLIAM A. FENN, of West Winfield, in the county of Herkimer and State of New York, have invented certain new and useful Improvements in Type-Holders; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

The object of my present invention is to provide a type-holder adapted for holding the removable type of hand-stamps such as are used in post-offices for canceling stamps and marking letters. When no device is employed for holding the type and keeping them in their order, they are prone to become confused and require considerable time and patience to select the proper type. Sundry devices have been heretofore provided for in a measure overcoming this difficulty.

The object of my device is to provide a convenient case-holder which will effectually hold the type in order and from which they can be removed with facility by employing only one hand and in which they can be carefully examined and cleaned.

In the drawings, Figure 1 shows a front elevation of my improved type-case filled with type. Fig. 2 shows a side elevation of the same in its normal position. Fig. 3 shows a side elevation after the type-ejector has been operated. Fig. 4 shows a perspective view of the device with the type removed. Fig. 5 shows a side elevation of a modified form of construction in its normal position. Fig. 6 shows a side elevation of the same after the device has been operated to eject the type. Fig. 7 shows a cross-section taken on line A B of Fig. 2 with the parts in the same position in which they are shown in Fig. 2. Fig. 8 shows a section taken on line C D of Fig. 3 with the parts in the position in which they are shown in that figure.

Referring to the reference letters and figures in a more particular description, 1 indicates the body or casing, which is mounted on a backing or base piece 2 by being secured thereto at the point 3 at the upper end and

at the lower end by the projection 4, the casing being arranged at an angle with reference to the back 2, as shown particularly in Figs. 2 and 3. The casing is provided with side walls and rear walls, as shown, and inwardly-turned edges 1^a 1^a on the side walls. In the construction as shown in the drawings there is also provided a middle partition 5, dividing the casing into two vertical spaces, adapted to receive two columns of type, although it is obvious that the partition 5 can be omitted and the case contracted laterally, so as to hold only a single column of type. When the two columns are employed, one is used for numbers or dates, while the other is used for characters designating or abbreviating the names of the month. At the upper end the inwardly-turned edges 1^a are cutaway, as shown at a a, making provision for the introduction of the type into the case. The inwardly-turned edges 1^a of the case are also cut away at the lower end, as indicated by b b, forming openings at which the type may be ejected. Secured on the back of the case at 6 is a flat spring 7, provided on its lower end with a pair of ejector projections 7^a, which are arranged to operate through openings in the back of the case at the lower end opposite the cut-away portions 7^b 7^b on the front of the case. The ejector-spring, with the ejectors, is operated by an angular or bell-crank lever 8, which, as shown, is formed of wire, the inner end or short arm 8^a being enlarged and occupying a position back of the spring 7 and on top of the projection or support 4, the arm of the lever passing out through the opening 4^a in the projection or support 4.

The device when filled with type in order is adapted to be hung on the wall and is operated by forcing the lever-handle 8 from the position shown in Fig. 2 to that shown in Fig. 3. In this operation the ejector projections 7^a engage with the lowest type in each of the two columns and force them from their position within the case to a partially-ejected position, as shown in Fig. 3. The length of the projections 7^a is such as to produce this result and not fully eject the type, the back of the case acting as a stop for the ejector. In this position—that is, the position shown in Fig. 3—the partially-ejected type are held by the weight of the column of type above

them. After being partially ejected the lever 8 is released, when it immediately assumes its normal position by reason of the tension of the spring 7. The operator then 5 takes hold of the type and removes them from the case, when the column of type drops down, bringing another type into position to be ejected by a successive operation. After the type has been used it is replaced in the holder. 10 at the head of the column through the cut-away portion or opening *a*. The length of the device is preferably such that the number of type in use will fill the column. It will be noted that the face of the type are 15 continually exposed to view, and they may be cleaned with a brush or other means in the holder and without removing.

In the modified form of construction shown 20 in Figs. 5 and 6 the body or casing 1^a is secured on the back 2^a at the point 10 by a spring which normally holds the casing at an angle with the back 2^a, as shown in Fig. 5. The ejector projection 11 is secured to the back 2^a at the lower end of the casing and in 25 position to enter openings in the back of the casing and partially eject the type, when the casing is forced toward or against the back, as shown in Fig. 6. In order to facilitate the movement of the casing toward the back, 30 there is provided a dependent projection 12 on the case, against which the thumb or finger can be readily placed to move the casing. After the type has been partially ejected in 35 this construction the casing is released and it assumes its normal position, as shown in Fig. 5, and the operator removes the type, and the column of type descends, as in the previously-described construction.

In either construction if the type from only

one column is used or there is some change 40 of purpose, the type may be readily forced back into normal position.

It is evident that other changes and modifications in and from the constructions described may be made without departing from 45 the spirit of my invention.

What I claim as new, and desire to secure by Letters Patent, is—

1. In a type-holder, a casing adapted to receive two vertical columns of type, an exit-opening at the foot of each column, an intake-opening at the head of each column, and a transversely-acting ejector located opposite the exit-openings and arranged to operate simultaneously on the type at the foot of each 55 column, and a stop to limit the movement of the ejector when the type is partially ejected, substantially as set forth.

2. The combination of a type-casing arranged to receive a vertical column of type, 60 and having on its front, inwardly-turned edges 1^a to retain the type in the case while exposing their faces and said edges 1^a being cut away at the lower end of the case, affording the type exit-opening, a spring-retracted 65 type-ejector arranged at the lower end of the case opposite the exit-opening to engage the lowest type of the column only, and means for limiting the movement of the ejector in ejecting the type when the type is only partially ejected, substantially as set forth.

In witness whereof I have affixed my signature, in presence of two witnesses, this 20th day of August, 1898.

WILLIAM A. FENN.
